UNITED STATES PATENT OFFICE.

WILLIAM H. HAMPTON, OF NEW YORK, N. Y., ASSIGNOR TO THE CONLEY ELECTRIC FURNACE COMPANY, INCORPORATED, OF WILMINGTON, DELAWARE, A CORPORATION OF DELAWARE.

ELECTRICAL FURNACE.

1,147,165.

Specification of Letters Patent. Patented July 20, 1915.

Application filed February 28, 1913. Serial No. 751,259.

To all whom it may concern:

Be it known that I, WILLIAM H. HAMPTON, a citizen of the United States, residing at New York, in the county and State of New York, have invented Improvements in Electrical Furnaces, of which the following is a specification.

This invention relates more especially to metallurgical furnaces, and may be used for 10 various processes and operations wherein it is necessary or desirable to admit air or gases, or any gaseous fluid, to act on the ore or material being treated. The furnace illustrated herewith is designed more particularly for a roasting furnace, but it may also 15 be used for drying or calcining material, and the principles of the invention may be adapted for still other purposes.

The object of the invention is to provide 20 a furnace of this general character in which the means for admitting the air or gases is so combined with means for directing and controlling the flow of the material as to secure the most advantageous action by the 25 gaseous fluid on the material, which is being roasted or otherwise treated. The material is heated by heated guide surfaces, the arrangement of which promotes the action of the air or gases on the material, and 30 to this end part or all of the parts affording said surfaces are provided with non-arcing resistance conductors, in the manner set forth in my companion application filed February 28, 1913, Serial No. 751,258.

35 In the accompanying drawings illustrating the invention: Figure 1 is a vertical section through the furnace; and Fig. 2 is a horizontal section on the line 2—2 of Fig. 1.

The furnace is a vertical structure and 40 may be regarded as comprising a shaft provided with a plurality of guide members, which break up its interior and guide the material in a zigzag course in its descent by gravity. The shaft 10 is suitably built of 45 masonry and has a lining 11, which may be of acid, basic or neutral character. The material is admitted through an opening 12 in the top, and is shown as supplied from a hopper 13 by a feed screw 14, which may 50 be operated intermittently or continuously, as desired. The guide members preferably comprise approximately triangular blocks 55 and 16, the former projecting inward from the sides of the furnace and the latter being located centrally. The side members

15 may be regarded as single blocks and the middle members 16 as double blocks. Thus, at each side of the vertical center line there is a zigzag or a staggered series of guide members 16, 15, 16, 15, having reversely 60 sloping surfaces which deliver the material from one to the other. These blocks partially divide the interior of the shaft into cavities, which communicate with each other by comparatively narrow gaps where the 65 lower edge or corner of each block approaches the sloping side of the one next below. The uppermost central block 16 is located directly below the feed opening 12, and consequently parts the material, as it 70 enters, to right and left, so that two streams are formed which diverge and converge repeatedly as they flow downward over the sloping surfaces. Inasmuch as the streams may join at the lower edges of the several 75 blocks 15 and the edges of the blocks 16, it will be understood that the streams are not necessarily distinct throughout their flow. Obviously, the size of the furnace may be increased and the number of blocks multiplied, and there may be any number of zigzag streams that may be desired. The characteristic arrangement is such, however, as to cause the material to flow over the heating surfaces in one or more zigzag streams 80 or sheets, so that the material repeatedly changes its course, is turned over and over and becomes thoroughly mixed and exposed to the action of the heat and air or gases before it finally reaches the lower part of the 85 furnace. The latter is preferably in the form of a hopper 17, from which the material may be drawn off continuously or intermittently through the central opening 18, which may be closed or controlled by any 90 suitable means, represented at 19.

The air or gases are supplied by a blower 20, which forces the gaseous fluid through a duct 21 in the lower part of the masonry. This duct is extended, as shown at 22, so as 100 to cause the fluid to flow around the hopper bottom 17. The duct 22 delivers the fluid thus heated to a distributing system, comprising an upward-extending duct 23 in one of the side walls of the shaft and lateral branch ducts 24 which terminate in ports 25 that deliver into the side cavities below the blocks 15, which are preferably recessed at the bottoms to afford pockets into which these ports open. The branch passages 24 105 110

may be extended rearward to the exterior of the shaft for purposes of cleaning, their rear ends being normally closed by blocks 40. Means are provided for conducting off 5 the resulting gases or vapors from levels between those at which the air or gases to act upon the material are admitted. To this end ports 26 are provided, which lead from the central cavities beneath the central blocks 10, which are preferably also recessed at the bottom to provide pockets for the collection of gases, and these ports constitute the entrances to ducts 27, which lead through the walls of the shaft into a common vertical 15 duct or chamber 28 at one side of the shaft and preferably formed in the wall thereof. This space has an opening at the bottom provided with a closure 29 for removal of collected dust, etc., and at the top has an exit 20 opening 30 through which the gases pass to another collecting or separating chamber 31. The latter is provided with a depending partition or baffle 32, an opening with a closure 33 at the bottom for removal of the 25 dust, and an exit 34 at the top from which the gases may be conducted to any desired point or allowed to escape.

Means are provided for heating the material electrically as it flows over the inclined 30 guide surfaces. To this end the blocks 15, 16 are provided in their interiors with non-metallic resistance conductors 35, which become incandescent on passage of electric current and are adapted to afford a high 35 degree of heat. These conductors are suitably formed of a composition of clay and graphite in approximate proportions of sixty per cent. of clay to forty per cent. of carbon. The heating elements by being embedded or inclosed in the blocks are protected from the charge and from gases or air which may be formed in or admitted to the shaft. The blocks are of heat-resisting, 40 electrically non-conducting material, and their upper sections may be carborundum tiles. The lower sections may be also carborundum tiles if desired. At their ends the conductors are received in socketed connections 36 of a lower degree of resistance, 45 which in turn receive pure carbon terminals 37 that are electrically connected by bars 50 to suitable members 38, which make connection with the outside circuit or circuits. The bars 50 are bolted or otherwise secured 55 in close electrical connection to the carbon terminals 37, and are also in close electrical connection with the members 38. Thus, the 60 surfaces of the deflectors, which guide the flow of the material and divide the interior of the shaft in such manner as to secure the best action of the air or gases on the material, are heated by controllable means which enable the material to be heated to any desired degree without interfering with the 65 downward flow of the material or the up-

ward movement of the air or gases. The arrangement of the air or gas inlets and of the gas or vapor outlets at alternating levels, between which are the comparatively narrow gaps where the material is turned, 70 agitated and given a new direction, is especially advantageous. Certain of the blocks need not be provided with the resistance heaters, or if in operation it is found that the material contains enough of certain constituents to continue burning after being ignited, current may be passed only through the conductors of the upper block or blocks to ignite the material and through the conductors of the lowermost blocks to complete 75 the roast or other treatment.

Means are provided for independently regulating the degree of heat at different levels. To this end the heating units 35 at the different levels are connected in multiple 80 by conductors 44, 45 across the main conductors 46, 47 of the secondary circuit of a transformer 48, and variable resistances or inductances, represented at 49, control the amount of current supplied to each set of 85 resistance conductors 35.

In operation, the air or gases are forced in by the blower 20 and caused to travel around the hopper bottom 17, where they are heated to facilitate the subsequent reactions 90 in the portion of the shaft containing the deflectors. The air or gases emerge through the ports 25 at different levels, and in rising through the circuitous spaces between the blocks become thoroughly mixed with the 95 descending zigzag streams of material, so that by the aid of the heat supplied at the deflecting surfaces by the resistance conductors the roasting or other operation is performed in a most efficient manner.

The rate at which the material is supplied to the series of surfaces and the rate at which it flows therefrom, and consequently the velocity and volume of flow through the shaft and over the heating surfaces, can be 100 regulated by valves or gates, indicated in a schematic manner at the top and bottom, those at the top being designated by the numerals 41, 42, and the one at the bottom being numbered 43. The construction and 105 operation of the gates or valves may be widely varied. The lower gate 43 is represented as being slidable on guides or ledges, and is movable by means of a poker or the like inserted through the lowest of 110 the openings 24.

What is claimed as new is:

1. In an electric furnace, the combination of a shaft, guide blocks arranged in staggered relation down the interior thereof and having reversely sloping surfaces adapted to cause the material to flow thereover by gravity in a zigzag downward course, non-arcing resistance conductors located in the interior of part or all of said blocks to heat the slope- 115

ing surfaces thereof and the material flowing thereover, means for supplying gaseous fluid to the shaft at different levels, and means for conducting the resulting gases and vapors away from the shaft at intermediate levels.

5. A furnace having a shaft, a plurality of triangular blocks of refractory material disposed therein in staggored relation, means for supplying heat to the material as it flows over the surface of said blocks comprising carbonaceous resistance elements located in the interior of said blocks, and means for delivering gaseous fluid into the shaft beneath certain of said blocks to react with the heated material.

10. A furnace having an interior in which the material is caused to flow downward by gravity, the same being provided with a plurality of guide members disposed at successive levels and having sloping surfaces in zigzag relation over which the material flows in a like course, means for electrically heating the material in the shaft comprising resistance elements located in the interior of part or all of said members, means for admitting gaseous fluid into the shaft beneath guide members at different levels, and means for conducting off the resulting gases and vapors from beneath guide members at intermediate levels.

15. In a furnace, a shaft into which the material to be treated is fed at the top, guide members therein for causing the material to flow in a zigzag course as it descends by gravity, and a portion at the bottom of the shaft for receiving the material that finally

20. drops from the lowest guide members, in combination with a duct for admission of gaseous fluid arranged adjacent the wall of said bottom portion so as to be heated by the material therein, and distributing ducts with ports opening into the interior of the shaft to which the fluid flows from the heating ducts.

25. A vertical furnace provided interiorly with guide members arranged to cause the material to flow in a zigzag course in its descent by gravity, means for heating the material in its descent, an exit for gases and vapors, and means for conducting gaseous fluid to act on the material around the lower portion of the interior of the furnace to be heated and then admitting it to the portion of the interior containing the guide members.

30. A furnace having a downward extending opening or passage therein and a plurality of guide members in said passage, said guide members having reversely sloping heating surfaces arranged to cause the material to flow thereover in a zigzag course, non-arcing resistance heaters for heating said surfaces, means for regulating the flow over said surfaces, and means for introducing gaseous fluid to act on the material while flowing over said heating surfaces.

35. In testimony whereof, I have signed by name to this specification, in the presence of two subscribing witnesses.

WILLIAM H. HAMPTON.
